UNITED STATES PATENT OFFICE

125,325

DESIGN FOR A CASING FOR WINDOW VENTILATING UNITS

William J. Campbell, Indianapolis, Ind., assignor to Climax Machinery Company, Indianapolis,
Ind., a corporation of Indiana

Application March 27, 1940, Serial No. 91,265

Term of patent 7 years

To all whom it may concern:

Be it known that I, William J. Campbell, a citizen of the United States, residing at Indianapolis, in the county of Marion, and State of Indiana, have invented a new, original, and ornamental Design for a Casing for Window Ventilating Units, of which the following is a specification, reference being had to the accompanying drawings, forming a part thereof.

In the drawings:

Fig. 1 is a rear elevational view of a casing for window ventilating units showing my new design;

Fig. 2 is a front elevational view thereof;

Fig. 3 is an end elevational view thereof seen from the left side of Fig. 1;

Fig. 4 is an end elevational view thereof seen from the right of Fig. 1; and

Fig. 5 is an isometric view of the casing for window ventilating units of Fig. 1.

The cross-hatched lines in Figures 1, 3, 4, and 5 represent foraminous metallic material which is only partially shown in the drawings but which covers all of the indicated spaces between the frame elements of my casing for a window ventilating unit.

I claim:

The ornamental design for a casing for window ventilating units, as shown and described.

WILLIAM J. CAMPBELL.
